UNITED STATES PATENT OFFICE.

HUBERT F. KRANTZ, OF BROOKLYN, NEW YORK, ASSIGNOR TO KRANTZ MANUFACTURING COMPANY, INC., OF BROOKLYN, NEW YORK, A CORPORATION OF NEW YORK.

SWITCH MECHANISM.

1,399,495.

Specification of Letters Patent.

Patented Dec. 6, 1921.

Application filed December 26, 1917. Serial No. 208,797.

To all whom it may concern:

Be it known that I, HUBERT F. KRANTZ, residing at Brooklyn, in the county of Kings and State of New York, have invented certain new and useful Improvements in Switch Mechanism, of which the following is a specification.

This invention relates to an improved motor starting switch.

10 The object of the invention is to provide a motor starting switch which is an improvement over the structure shown and described in my pending applications Serial Numbers 79,097 and 79,098 filed February 18, 1916.

15 A further object is to provide an improved motor starting switch in which is employed a single operating handle movable into three positions, "starting," "running," and "dead," and in which the handle, and the parts connected thereto, will automatically move into the "running" position after having been moved from "dead" to "starting" position.

20 A further object is to provide a no-voltage release for the mechanism.

25 A further object is to arrange all of the above mechanism within a safety container or panel box having an entrance door together with means whereby the door will be held against being opened except when the mechanism is in the "off" position.

30 A further object is to arrange a wall or barrier within the box disposed and adapted for carrying certain parts of the mechanism which it is desirable to reach upon opening 35 of the door and for guarding certain parts which are left live when the handle is moved to "off" position for opening the door.

35 A further object is to so mount the barrier that it may be readily inserted or removed as required.

40 A further object is to adapt the barrier to carry certain of the parts of the mechanism so that said parts may be lifted into or out of co-operative relation with the remaining parts by the act of inserting or removing the barrier.

45 Other objects and aims of the invention, more or less specific than those referred to above, will be in part obvious and in part 50 pointed out in the course of the following description of the elements, combinations, arrangements of parts and applications of principles, constituting the invention; and the scope of protection contemplated will be 55 indicated in the appended claims.

In the accompanying drawings which are to be taken as a part of this specification, and in which I have shown merely a preferred form of embodiment of the invention:

60 Figure 1 is a vertical transverse sectional view showing the device constructed in accordance with this invention, the section being taken substantially upon the plane of line I—I of Fig. 2.

65 Fig. 2 is a horizontal sectional view taken substantially upon the plane of line II of Figs. 1 and 3.

70 Fig. 3 is a front elevational view of the structure shown in Fig. 1, the front wall, or cover of the box being omitted.

Fig. 4 is a view similar to that shown in Fig. 3 but not with the barrier removed.

75 Fig. 5 is a fragmentary sectional view taken substantially upon the plane of line V of Fig. 1.

Fig. 6 is a diagrammatic view showing the movable switch elements of Fig. 1 when in the "starting" position.

80 Fig. 7 is a similar diagrammatic view showing the parts in "running" position.

Fig. 8 is a fragmentary elevational view of the portion of the box cover illustrating a means for preventing opening of the door except when the operating handle is in the 85 "off" position.

Fig. 9 is a sectional view taken upon the plane of line IX of Fig. 8.

Fig. 10 is a view similar to that shown in Fig. 8 but being taken from the reverse 90 side of the box wall.

Fig. 11 is an enlarged detail view illustrating a modified arrangement of the operating handle.

95 Fig. 12 is a horizontal sectional view taken substantially upon the plane of line XII of Fig. 11.

Fig. 13 is a front elevational view of the box showing the application of a door-locking device in connection with the operating 100 handle of Figs. 11 and 12, and

Fig. 14 is a detail sectional view taken substantially upon the plane of line XIV of Fig. 13.

105 Referring to the drawings for describing in detail the structure which is illustrated therein, the reference character L indicates a casing or box within which the parts of the device are contained. This may be of any suitable material but is preferably formed 110

from sheet metal. The front wall of the box comprises a narrow portion 1 which is fixed to the adjacent side walls and a door portion 2 which is hinged to the portion 1, as at 3.

5 The portion 1 is provided with a flange 4 by means of which it may be detachably fixed to the adjacent side wall.

10 Within the box is provided a base plate G which is of insulating material, such as slate, and preferably fixed flat against the rear wall 5 of the box.

15 This base plate carries three bus bars 6, 7 and 8 into which the main line wires 9 of a three-wire system lead. The bus bars are arranged vertically side by side in substantially parallel relation.

20 A barrier H, also of insulating material such as slate, is provided within the box. This barrier is arranged substantially parallel with the face of the base plate G and between said plate and the door 2. Upon its outer face it carries the fuse clips 10 and 11 for retaining fuses 12, 18 and 14 in a position of easy accessibility whenever the 25 door is open. Upon its inner face it carries two sets of contacts 15-16-17 and 18-19-20, each contact being connected through the barrier H with an adjacent fuse clip 10 or 11 by means of the connecting bolts 21 to serve to hold both fuse clips and contacts in position upon the barrier.

30 In the space between the rear surface of the barrier and the forward surface of the base plate is arranged a pair of switches 22 and 23 each of which comprise an elongated carrier supporting three double ended switch blades 24. The blades of the switch 22 are arranged to bridge between the bus bars 6, 7 and 8 and the contacts 15, 16 and 17 respectively, while the blades of the switch 23 are arranged to bridge between the bus bars 6, 7 and 8 and the contacts 18, 19 and 20 respectively.

35 The switch blades are insulated from each other and from the carrier by suitable insulating plates 25.

40 The opposite ends of the carriers are pivotally mounted, as at 26, in bracket plates 27 and 28 so that the carriers, with the blades, are adapted to swing about axes which extend parallel with each other and with the opposing surfaces of the base plate and the barrier.

45 The bracket plates 27 and 28 are disposed to serve as supports to which the barrier H is detachably connected, as at 29, they thereby defining the proper position for the barrier H so that the contacts 15-16-17 and 18-19-20 correctly coöperate with the 50 switch blades when the barrier is returned after having been removed for any reason.

55 The means employed for swinging the switch 22 into "on" and "off" positions comprises a pair of toggle links 30 which are connected between the carrier of said switch,

as at 31, and a fixed point 32 upon the bracket plate 28. When the toggle is "broken" the switch is "off" while when the toggle is "made" the switch is "on."

60 The operating handle 33 is pivotally mounted upon the bracket plate 28, as at 34. Its outer end projects outwardly from the casing through a slot 35 formed in the portion 1 of the front wall of the casing while its inner end is connected with a link 36 which in turn is connected with the heel of the toggle so as to "make" and "break" the toggle by swinging movement of the operating handle.

65 The connection between the inner end of the operating handle and the link 36 includes a pin 37 carried by the operating handle which engages within a slot 38 formed in the link 36 so as to permit unobstructed movement of the toggle to "broken" position immediately it passes "dead-center."

70 A spring 39 is provided for urging the switch 22 at all times toward the "off" position.

75 The switch 23 is operated in a somewhat different manner from the switch 22 and the operating means therefor includes an anti-friction roller 40 mounted upon the carrier of said switch at one side of the pivotal axis of the carrier, together with a cam link 41 which is connected with the pin 37 of the operating handle so as to be slid back and forth as the operating handle swings. When the operating handle swings toward the "on" position a steep incline surface portion 42 of the cam operates upon the roller 40 to swing the carrier rapidly toward the "on" position. When the switch blades have reached their respective contacts and bus bars then a less incline surface 43 of the cam slides over the roller 40 and presses the blades to full "on" position with considerable force.

80 A guide member 44 serves to retain the cam in operative association with the roller 40 and carries an anti-friction roller 45 to facilitate easy back and forth movements of the cam at all times.

85 The relation of the operating handle and the parts moved thereby is as follows. With the operating handle in the "dead" or "off" position the parts stand in the position shown in Fig. 1. The pin 37 is spaced an appreciable distance away from the upper end wall 46 of the slot 38 and the surface 42 of the cam link is spaced a less distance from the roller 40 so that downward movement of the handle will first cause the surface 42 to swing the switch 23 into near "on" position before the pin 37 will begin to move the switch 22.

90 By swinging the handle way down to "starting" position the pin 37 will engage the end wall 46 of slot 38, and move the link 36 upwardly to "make" the toggle. Before 95

the toggle is "made," however, the surface 43 will ride on to the roller 40 and press the blades of switch 23 tightly "on." By this arrangement a full "on" position is secured for switch 23 ahead of switch 22. Any desired means may be employed for limiting the "on" and "off" movements of the switch 22, but preferably the bracket 28 is provided with an arcuate slot 49 within which the heel pivot pin 50 of the toggle moves for this purpose, the pin 50 engaging the opposite ends of the slot.

With both switches "on" the parts are in the position shown in Fig. 6. The switch 23 is provided with a spring 39 similar to that described for switch 22 and this spring, exerting its pressure first against the inclined surface 43 and then against the inclined surface 42, causes the cam link to move downwardly and thus swing the operating handle part way back toward the "off" barrier. With the switches "off" the position, that is to the "running" position facts 15-16-17 and 18-19-20 together As the handle swings the pin 37 thereof moves downwardly along the slot 38 but does not reach the lower end wall 47 of said slot. Note that the outer end of the handle is larger and heavier than the inner end and that this outer end must be raised by the pressure from the roller 40 in order to move the pin 37 downwardly and that for this reason there is practically no upward movement of the outer end of the handle after the roller 40 has reached a "dead" position against the surface 48 of the cam link.

Movement of the roller 40 to swing the handle into "running" position is of course accompanied by movement of the switch 23 into "off" position, so that the parts now stand in the position indicated in Fig. 7.

With the parts in "running" position a slight upward movement of the outer end of the handle will move the pin 37 downwardly against the end wall 47 of the slot 38 and force link 36 downwardly a sufficient distance to "break" the toggle and allow the spring 39 to snap switch 22 "off."

The parts then again stand in the "off" position as in Fig. 1.

As indicated in the drawings, each of the switch blades is made up of a series of separate strips of conducting material. These strips combine to render the blades flexible so as to bend somewhat when their opposite ends are pressed into engagement with the respective contact surfaces, and this bending stores an energy in the blades tending to move them away from the contacts. In the case of the switch 22, the energy of the switch blades is particularly effective, as an auxiliary to the spring 39, to hold the toggle "made" and to cause the switch to snap suddenly and positively toward the "off" position immediately the toggle is "broken." In the case of the switch 23 the energy of the switch blades is particularly effective, as an auxiliary to the adjacent spring 39, to force the roller 40 along the surface 43 of the cam link 41 thereby to more effectually and positively move the cam link downwardly approximately to a point where the roller passes on to the steeper surface 42 of the cam link.

Any desired means may be employed for limiting the "on" and "off" movements of the switch 22, but preferably the bracket 28 is provided with an arcuate slot 49 within which the heel pivot pin 50 of the toggle moves for this purpose, the pin 50 engaging the opposite ends of the slot.

When the operating handle 33 is in the "off" position as in Fig. 1 both switches are factually protected behind the barrier so that though the door be opened, the bus bars can not be reached without first detaching the operating handle part way back toward the "off" barrier.

With the switches "off" the handle 33 is moved downwardly to "starting" position both switches

are moved to "on" position as in Fig. 6, but the starting switch 23 makes contact in

pressure from the roller 40 in order to move the pin 37 downwardly and that for this reason there is practically no upward move-

ment of the outer end of the handle after the roller 40 has reached a "dead" position against the surface 48 of the cam link.

Movement of the roller 40 to swing the handle into "running" position is of course accompanied by movement of the switch 23 into "off" position, so that the parts now stand in the position indicated in Fig. 7.

With the parts in "running" position a slight upward movement of the outer end of the handle will move the pin 37 downwardly against the end wall 47 of the slot 38 and force link 36 downwardly a sufficient distance to "break" the toggle and allow the spring 39 to snap switch 22 "off."

The parts then again stand in the "off" position as in Fig. 1.

As indicated in the drawings, each of the switch blades is made up of a series of separate strips of conducting material. These strips combine to render the blades flexible so as to bend somewhat when their opposite ends are pressed into engagement with the respective contact surfaces, and this bending stores an energy in the blades tending to move them away from the contacts. In the case of the switch 22, the energy of the switch blades is particularly effective, as an auxiliary to the spring 39, to hold the toggle "made" and to cause the switch to snap suddenly and positively toward the "off" position immediately the toggle is "broken." In the case of the switch 23 the energy of the switch blades is particularly effective, as an auxiliary to the adjacent spring 39, to force the roller 40 along the surface 43 of the cam link 41 thereby to more effectually and positively move the cam link downwardly approximately to a point where the roller passes on to the steeper surface 42 of the cam link.

Any desired means may be employed for limiting the "on" and "off" movements of the switch 22, but preferably the bracket 28 is provided with an arcuate slot 49 within which the heel pivot pin 50 of the toggle moves for this purpose, the pin 50 engaging the opposite ends of the slot.

When the operating handle 33 is in the "off" position as in Fig. 1 both switches are factually protected behind the barrier so that though the door be opened, the bus bars can not be reached without first detaching the operating handle part way back toward the "off" barrier.

With the switches "off" the handle 33 is moved downwardly to "starting" position both switches

are moved to "on" position as in Fig. 6, but the starting switch 23 makes contact in

pressure from the roller 40 in order to move the pin 37 downwardly and that for this reason there is practically no upward move-

ment of the outer end of the handle after the roller 40 has reached a "dead" position against the surface 48 of the cam link.

is pivotally mounted upon the face of the barrier, as at 57, and has a heel 58 at one side of the pivot which stands beneath the end 55 of the toggle break lever. At the 5 opposite side of the pivot the trip lever is elongated and is pivotally connected with the solenoid core 59. It also carries a weight 60 operating against the upward pull of the core tending at all times to raise the 10 heel 58 against the end 55 of the toggle break lever so as to swing the end 54 of the toggle break lever downwardly to break the toggle. Current for the coil 52 is derived from the fuse clips 11, as at 61 and 62 through wires 15 63 and 64 which lead upwardly along the face of the barrier to the opposite sides of the coil.

By this arrangement, the moment the starting switch is moved "on," current is 20 shunted through the wires 63 and 64 and the solenoid coil so that the core 59 of the coil is lifted leaving the end 54 of the toggle break lever free to move upwardly to allow 25 unobstructed movement of the toggle into "on" position, and this shunt circuit will be maintained through the running switch and fuses so long as the running switch is held "on," or until the current flowing through 30 the device is for some reason reduced or cut off. As soon as the current is reduced or cut off the power of the solenoid core will be lost and the weight 60 will drop causing the heel 58 to raise the end 55 of the toggle break lever so as to depress the end 54 and 35 immediately break the toggle. The switches will then stand in "off" position until manually returned.

In order to provide ample space for accommodating all the parts carried by the 40 bracket plate 28 the barrier H is made of such width as to provide an ample opening at one edge thereof, as at 65, and a safety guard plate 66 is provided to prevent access through this opening to any of said parts 45 or to the parts at the rear of the barrier.

The guard plate 66 is preferably fixed to the portion 1 of the front wall of the casing and extends into the casing so as to form a vertical compartment 67 between itself and 50 the adjacent side wall of the casing within which compartment the various levers, etc., are contained. A slot 68 is provided for entrance of the heel portion of the trip lever 55 and a further slot 69 is provided in register with the slot 35 through which the operating handle 33 projects. A part 70 of the guard plate stands in position behind the crack which appears at the hinge of the door, said part 70 thereby preventing possibility of insertion of any foreign tool or 60 implement through the hinge crack.

The outer wall of the slot 68 serves as a simple expedient for retaining the lever 56 upon its pivot 57, though, if desired, an ex-

tra pin or other auxiliary fastening means 65 may be employed for this purpose as shown.

In order to prevent the insertion of a foreign tool or implement through the slot 35-69 a sliding guard plate 71 is provided just inside of the portion 1 of the front 70 wall. This guard plate is slidably mounted in clips 72 fixed to the guard plate 66 and is formed with a recess 73 which is just of sufficient size to accommodate the operating handle. As the handle moves up and down 75 the guard plate also moves up and down and at all times provides portions, as 74 and 75, which underlie the entire length of the slot 35-69 except the portion occupied by the operating handle. 80

Fixed to the outer surface of the door 2 is a guard plate 76. This plate projects laterally from the door in a position parallel with and close beside the slot 35. Its lower end extends substantially to the lower end 85 of the slot while its upper end terminates short of the upper end of the slot. Its flat surface thus stands in position lapping the side of the operating lever at all times except when the operating lever is in the full 90 "off" position, as seen in Fig. 9. Any effort to open the door while the operating handle is in other than the full "off" position will be resisted by engagement of the plate 76 against the operating handle, while 95 any effort to move the operating handle downwardly from "off" position while the door is open will be resisted by engagement of the operating handle against the upper edge of the plate. 100

Thus the door may not be opened except when the handle is "off" and the handle may not be moved "on" except when the door is closed. All of the current carrying parts upon the face of the barrier are therefore necessarily dead whenever the door is open but may be made dead or live at will while the door is closed. 105

Whenever, for any reason, it is desired to remove the front wall of the casing it is 110 simply necessary to withdraw the screws 76 which hold the flange 4 fixed to the adjacent side wall of the casing, and remove the handle grip 77 from the handle lever, whereupon the front wall may be bodily lifted 115 out. The slide 71 may then be removed or repaired if desired. The barrier H may also then be removed by simply disengaging the screws 29. This will leave the switches and 120 their manual operating elements, including the operating handle, all in assembled operative condition ideally exposed for inspection, adjustments, and repairs.

As many changes could be made in this construction without departing from the 125 scope of the invention as defined in the following claims, it is intended that all matter contained in the above description or shown

in the accompanying drawings, shall be interpreted as illustrative only and not in a limiting sense.

By referring to the illustrations Figs. 11 and 12 it will be seen that a modified arrangement of the operating handle and its associated parts may include mounting the pivot member of the handle to extend through the adjacent side wall of the casing 10 so as to carry a part of the operating handle within the casing and another part without the casing. This arrangement lends itself to a modified device for retaining the door closed during use of the switch. It also 15 lends itself readily to the employment of locking means whereby the operating handle may be locked in the "off" position whenever desired, and also to the provision of means to insure return movement of the 20 operating handle to the "running" position.

A detailed description of the structures Figs. 11 and 12 is as follows:

The pivot member for the operating handle comprises a short shaft 78 which is mounted to rotate within a bearing sleeve 79 fixed to and extending through the side wall of the casing so as to give the shaft an ample bearing surface. 25 The inner end of the shaft is squared, as at 80, and carries a short arm 81 which in turn supports the pin 37. A washer 82 and a cotter pin 83 serve to removably retain the arm 81 upon the squared portion of the 30 shaft, and incidentally to retain the shaft against withdrawal outwardly through the bearing sleeve.

The handle lever 84 is fixed to the outer end of the shaft 78, as by means of a cross pin 40 85 or the like. This handle lever may carry the hand grip 77 and is adapted to be swung up and down between "off", "starting" and "running" positions for operating the pin 37 in the same manner as above described 45 with regard to the structure of the other figures.

In order to prevent opening movement of the guard door of the casing while the handle is in any but the "off" position, the door 50 is provided with an extension member 86 which projects beyond the pivot, as 87, of the door. The handle lever is provided with an arcuate surface portion 88 which swings downwardly into the path of movement of 55 the extension 86 whenever the handle is moved from the "off" position. While the handle is in the "off" position, however, the extension 86 is free to swing beneath the surface portion 88, as will be clearly apparent 60 from inspection of Fig. 11.

By arranging the handle lever 84 exteriorly of the casing said handle lever may be readily weighted so as to give it a natural tendency to assume an "off" position. The 65 weight is intended to be sufficient to serve,

as an auxiliary to the cam action of the surfaces 42 and 43 of the link 41, to move the handle from the "starting" to the "running" position, but it is not sufficient to move the handle from the "running" to the "off" position, as during this latter movement the effectiveness of the surfaces 42 and 43 is lost.

In order to lock the handle lever in the "off" position said lever is provided with 75 an eye 89 which stands adjacent to a bracket 90, also having an eye, as 91. Any form of locking element, such as a pad lock, may be inserted through the mating eyes 89 and 91 so as to prevent any movement of the 80 handle lever.

The door-locking lever 92, shown in Figs. 13 and 14, is pivotally mounted preferably upon the outer surface of the door, as at 93. An operating knob, as 94, is connected with 85 the lever at the pivot and serves as means by which the lever may be manually moved into unlocking position whenever desired while the handle lever 84 is in the "off" position. The knob 94 may incidentally be 90 used as a handle for swinging the door opened or closed.

The lever 92 is pivotally mounted relatively near to the free edge of the door and has a short arm 95 adapted to be moved 95 into and out of position within a slot 96 formed in a bracket 97 which is connected with the stationary wall of the casing in the manner indicated at 103 in Fig. 2. A relatively long arm 98 of the lever projects 100 into the path of movement of an extension piece 99 which is connected with the handle lever 84. A retaining bracket 100 may be arranged over a portion of the long arm of the lever so as to maintain it at all times 105 in proper operative position and so as to serve, if desired, as means for limiting the extent of movement of the lever.

By this construction it is apparent that whenever the handle lever 84 is depressed 110 either into the "starting" or "running" positions, the lever 92 is necessarily swung so that the end of its short arm 95 engages within the slot 96 and positively retains the free edge of the door against swinging. The 115 three arrows marked "off," "starting" and "running" indicate the position to which the lower end of the part 99 moves in accordance with the three indicated conditions of the switch mechanism. It is thus seen that the end 95 of the lever will engage within the slot 96 at all times while the switch is either "starting" or "running" and is only free from the slot 96 when the lever is in the "off" position.

It is intended that the long arm 98 of the lever shall be of such weight as to cause the lever normally to stand in locking position as indicated by the dotted lines 101 as by this means the door is maintained against 130

swinging open whenever the switch is "off" except by a positive manual rotation of the knob 94.

The extension stop 86 for engaging the arcuate surface portion 88 of the handle lever 84 may, if desired, be dispensed with where the lever 92 is employed, or both may be retained as auxiliaries to each other. The parts 86 and 88 in any event, however, serve the useful purpose of positively preventing the "on" movement of the handle 84 after the door has been opened.

Where the lever 92 is employed, of course it becomes unnecessary to employ the spring catch 102 as shown in Fig. 2.

Having thus described my invention what I claim as new and desire to secure by Letters Patent is:

1. A safety switch mechanism comprising a casing having an entrance door thereto, switch blades within the casing, a barrier within the casing interposed between said switch blades and the door, switch operating mechanism at one side of the casing having connection with the switch blades and having movable parts projecting in front of the barrier, and a guard member arranged within the casing between the door opening and said movable parts to guard said movable parts when the door is open.
2. A safety switch mechanism comprising a casing having a removable cover, switch blades within the casing, a barrier with the casing interposed between said switch blades and said removable cover, switch operating mechanism at one side of the casing having connection with the switch blades and having movable parts projecting in front of the barrier, and a guard member arranged with-

in the casing carried by said removable cover, the removable cover including a door for giving entrance into the casing and the guard member being arranged to protect said movable parts when the door is open.

3. Switch mechanism comprising a housing having an opening therein, a door for the opening, a switch within the housing, a detachable barrier within the housing interposed between the switch and the door, switch-operating mechanism within the housing and operable from the exterior thereof, and an electrically-actuated means mounted on, and removable with, the barrier and engaging the switch mechanism for actuating the switch mechanism under predetermined current conditions.

4. Switch mechanism comprising a housing having an opening therein, a door for the opening, a switch within the housing, a detachable barrier within the housing interposed between the switch and the door, switch-operating mechanism within the housing and operable from the exterior thereof, fuse devices mounted on the barrier and connected to the switch mechanism, and electrically-actuated means connected to the fuse devices and mounted on, and removable with, the barrier and engaging the switch mechanism for actuating the switch mechanism under predetermined current conditions.

In testimony whereof I affix my signature in the presence of two witnesses:

HUBERT F. KRANTZ.

Witnesses:

MAY SCHULZ,
HERBERT L. REX.
